CLAIM

The ornamental design for a personal work table, as shown and described.

DESCRIPTION

FIG. 1 is a perspective view of a personal work table; FIG. 2 is a top view of the personal work table shown in FIG. 1;

FIG. 3 is a right side view of the personal work table shown in FIG. 1, with the left side view being a mirror image thereof;

FIG. 4 is a front view of the personal work table shown in FIG. 1;

FIG. 5 is a back view of the personal work table shown in FIG. 1; and,

FIG. 6 is a bottom view of the personal work table shown in FIG. 1.

The broken lines are for illustrative purposes only and form no part of the claimed design.
